[57] CLAIM

The ornamental design for a humidifier for brown sugar, as
shown and described.

DESCRIPTION

FIG. 1 provides an isometric view of a humidifier for brown
sugar showing my new design;

FIG. 2 and 3 provide front and rear elevation views, respec-
tively, thereof;

FIG. 4 and 5 are top and bottom elevation views, respec-
tively, thereof; and,

FIG. 6 provides a side elevation view thereof, the opposite
side being substantially a mirror image of the illustrated
side.
